BOBBIN WHIRL GEAR

William F. Lee and Joseph B. Allen,
Glendale, S. C.

Application August 25, 1945, Serial No. 612,644

1 Claim. (Cl. 57—102)

1

Although our invention, in its broadest aspects relates to improvements in gears generally, it has particular reference to the bobbin supporting and driving whirl gears of the roving frames employed in cotton mills.

Briefly and generally stated, the invention has for its primary object to effect economy of metal by providing a long-lived gear which is made so by employing separable parts, such as the gear teeth per se and others.

More specifically, it is an object of the invention to provide a bobbin whirl gear or the like, having not only a replaceable gear tooth portion but also a replaceable bobbin driving clutch pin.

Heretofore, one of the primary objections to bobbin whirl gears has been that they are cast in one piece and the bobbin confining collar has a tendency to break as the result of the combination of strain and heat action. Also, the tubular bearing portion of such gears is of the same material as the gear and therefore required frequent oiling. Having the foregoing in mind, it is an outstanding aim of the instant invention to incorporate in a bobbin whirl gear or the like a novel sleeve of bearing metal which requires but little oiling and which also has a projecting portion for reception in the medial bearing of a bobbin in lieu of the conventional collar which is integral with the gear and when broken necessitates replacement of the entire bobbin whirl gear structure.

The foregoing and other objects which will be better understood later on, are attained by means of a novel combination and arrangement of parts to be hereinafter described and claimed, reference being had to the accompanying drawing, wherein—

Fig. 1 is an elevational view illustrating the application of our invention to a bobbin whirl gear and showing certain conventional elements immediately associated therewith;

Fig. 2 is a vertical sectional view through said bobbin whirl gear taken on the line 2—2 of Fig. 1;

Fig. 3 is a detailed sectional view illustrating our novel replaceable bobbin clutch pin, the view being taken on the line 3—3 of Fig. 1.

Referring to the drawing by reference characters which have been used to designate the same parts in all views, numeral 5 denotes generally a bobbin whirl gear, a fragment of a bobbin supported thereby being illustrated in dotted lines by numeral 4.

The whirl gear 5 is illustrated as rotatably journaled upon the usual bolster 6 through which

2

extends the conventional spindle 7 for supporting a flyer (not shown).

The bolster 6 has a lower portion 6a which supports the drive shaft 8 upon which is keyed the skew bevel gear 9 having driving engagement with the lower gear toothed portion 5a of said bobbin whirl gear 5.

In carrying out the invention, we provide the lower end of the sleeve portion 10 of said whirl gear 5 with a threaded connection 10a between it and the removable toothed annulus 5a.

The threads which provide the connection 10a between sleeve 10 and the toothed gear annulus 5a will be either right-hand or left-hand but said threads preferably have such relation to the direction of rotation of the skew bevel gear 9 as to effect a tightening of the toothed annulus 5a on the sleeve 10 in the normal operation of the device.

As heretofore intimated, much of the breakage of bobbin whirl gears, whether it be as to the teeth or the bobbin confining collar, is due to over-heating of the sleeve bearing which surrounds the bolster 6. We meet this difficulty by providing a separate bearing sleeve 12 which is insertable into the sleeve portion 10 of said gear and sweated or otherwise retained in place. The upper end of said separate bearing sleeve 12 projects above the circular bobbin supporting flange 11 to provide a bobbin confining collar 12a. The separate bearing sleeve 12 will preferably be made of brass or other wear-resisting material, which requires but little oiling and is resistant to heat penetration. Various metal alloys commonly used for bearings may be used to advantage.

Also, the bobbin clutch or drive pins which seat in a recess 4a in the bottom of the bobbin 4, have a tendency to break and we meet this objection to the conventional bobbin whirl gear by providing a removable clutch pin 13 whose shank is threaded into the bobbin supporting flange 11 as illustrated in Figs. 1 and 3. This removable bobbin clutch pin 13 has a kerf 13a across its top for the reception of a screw-driver.

The conventional flange 14 surrounds the exterior sleeve portion 10 of the gear as usual to protect the operator's fingers against contact with the gears 5a, 9 when he is placing or removing a bobbin 4 upon the upper circular flange 11.

From the foregoing description, taken in connection with the accompanying drawing, it will be apparent that the mill owner using our bobbin whirl gear will be saved a tremendous amount of expense. If the toothed gear portion 5a breaks

or when it becomes worn as it does in service, it can be readily screwed off the sleeve 10 and another gear section 5a put on in its place. If the clutch pin becomes broken, it can be conveniently replaced also, and in practice it will probably be desirable that the shank of said clutch pin 13 be smooth so it can be driven out of the aperture in the flange 11. The dual advantage of the separate bearing sleeve 12, 12a has already been emphasized.

Having thus described our invention, what we claim as new is:

A bobbin-supporting whirl gear for a cotton mill roving frame or the like and comprising a tubular body portion extending from one end, a laterally projecting bobbin-supporting portion at the upper end of said body portion, a bearing sleeve of wear-withstanding material insertable in said tubular body portion and tightly fitting therein, said bearing sleeve projecting beyond the plane of said bobbin-supporting portion whereby to provide a bobbin-centering means, and a toothed annular gear portion removably receiving

said tubular body portion and secured thereto inwardly of said bobbin-supporting portion.
